ELECTRIC STARTER SYSTEM

Bennett M. Leece, Shaker Heights, Ohio, assignor
to The Leece-Neville Company, Cleveland, Ohio,
a corporation of Ohio

Application November 18, 1935, Serial No. 50,294

6 Claims. (Cl. 172—291)

This invention relates to electric control apparatus, and more particularly to control apparatus which is useful in connection with the starting motors of internal combustion engines and in connection with various other motors and electrical equipment.

An object of the present invention is to provide improved electrical control apparatus embodying novel means for preventing sticking of switch contacts.

Another object of this invention is to provide improved electric control apparatus wherein a magnetically actuated member is arranged to cause opening of switch contacts to overcome sticking thereof.

A further object of this invention is to provide improved control apparatus wherein a magnet actuated member is arranged to cause opening movement of switch contacts to overcome sticking thereof, and wherein the energizing circuit for the magnet is established through the sticking contacts.

Still another object of this invention is to provide electric control apparatus wherein a switch controlled magnet causes closing of a pair of contacts when energized and permits opening of the contacts when deenergized, and wherein a magnet operated striker causes opening of the switch contacts to overcome sticking thereof, the circuit for the striker magnet being established through contacts of the switch and through the sticking contacts.

It is also an object of this invention to provide an improved electric starter system comprising a switch with a manually operable member normally held in an initial position but movable to a second position, a magnet which is energized to close a pair of load contacts when the manually operable switch member is in its second position, and a magnet actuated striker which acts to overcome sticking of the load contacts and which is energized whenever the switch member is in its initial position and the load contacts are closed.

Other objects and advantages of the invention will be apparent from the following description when taken in conjunction with the accompanying sheet of drawings, wherein

Fig. 1 is a diagrammatic view illustrating an electric control system embodying my invention; and

Fig. 2 is a diagrammatic view showing a similar but a somewhat simplified control system.

The electric control system of my invention may be applied to various uses but is especially useful in connection with electric starting motors

of the kind commonly used for cranking internal combustion engines. While the control systems shown in the drawing will be hereinafter described in connection with electric starting apparatus, it should be understood, however, that my invention is not necessarily limited to this particular field of use.

In the control system illustrated in Fig. 1 of the drawing, I have shown an electric motor 10, which may be the driving motor of an electric 10 starter device, and a source of energizing current for the motor, such as a storage battery 11. A manually operable switch 12 establishes circuit connections which, as will be presently explained, cause the desired operation of the starting motor 10. My control system also includes a magnetically operated switch or contactor 13 in the motor circuit and a magnetically actuated device 14 for overcoming sticking of the contacts of the latter switch.

The control switch 12 may be of any construction suitable for the service which it is to perform. For example, as shown in the drawing, this switch may comprise a suitable insulating base 16 provided with a plurality of stationary contacts 17, 18, 19, 20, and 21, and a movable contact 22 which may be actuated by any suitable manually operable control, such as the hand lever 23 extending from the switch base. The hand lever 23 is operably connected with a barrel or sleeve 24 30 which carries the contact 22 such that by manipulation of the hand lever the contact will be moved or swung into engagement with different sets or pairs of the stationary contacts. The switch base may be provided with a pivot pin or shaft 25 on 35 which the sleeve 24 and the hand lever 23 are suitably mounted.

The contact 22 may be in the form of a metal rim which is mounted upon a roller 26 formed of insulating material. This roller is rotatably carried by a block 27 which is slidable in the sleeve 24 and is normally urged outwardly thereof by a coil spring 28. The stationary contacts of the switch 12 are preferably disposed in arcuate arrangement, as shown in the drawing, so that 45 when the sleeve 24 is swung about the pivot 25 by means of the hand lever 23, the contact 22 will roll over the stationary contacts.

The stationary contacts shown in this instance are sufficient in number to provide three different 50 stations or positions for the movable contact 22. The first or initial position of the movable switch contact 22 is indicated by the line 30, and when the contact is moved to this position, it electrically connects the stationary contacts 17 and 18. 55

The second position for the movable contact 22 is indicated by the line 31, and, when in this position, the contact electrically connects the stationary contacts 18 and 19. A third position to which the contact 22 may be moved is indicated by the line 32, and when the contact is in this position, it electrically connects the stationary contacts 20 and 21. An insulating arm 33 may be provided between the stationary contacts 19 and 20, the arm being of such form that it is engaged by the contact 22 and prevents the latter from establishing an electrical connection between the contacts 19 and 20 as it passes thereover.

As will appear more fully hereinafter, it is important in the operation of my control system that the movable switch contact 22 be normally held in or returned to the position 30 so as to electrically connect the contacts 17 and 18. To this end I provide suitable means, such as the coil spring 35, which is disposed around the pivot pin 25 with one end thereof engaging a projecting part 36 of the sleeve 24 and the other end thereof anchored on a projecting part 37 of the contact 17. By reason of the spring arrangement shown and described, it will be seen that the contact 22 is normally held in engagement with the contacts 17 and 18 but is movable from this initial position to the positions 31 and 32. If desired, a suitable stop 38 may be provided adjacent the contact 21 to prevent movement of the contact 22 beyond a predetermined point.

When the hand lever 23 is operated to move the contact 22 from the position 30 to the position 31, the contacts 18 and 19 are electrically connected to establish a low voltage energizing circuit for the motor 10. By means of the circuit thus established, current is supplied to the motor from the battery 11 at a low voltage, for example, six to eight volts. This energizing circuit may be traced as follows: From terminal 40 of the battery 11 through conductor 41 to motor 10, then through conductors 42 and 43 to switch contact 18 and through movable contact 22 to stationary contact 19, and then back to the terminal 44 of the battery through the conductor 45.

When the switch member 22 is moved to the position 32 by further swinging of the hand lever 23, the contact 22 connects contacts 20 and 21 and causes energization of the magnetic switch or contactor 13 to close the load contacts 47 and 48. The closing of these load contacts establishes another circuit for the starting motor 10 whereby current is supplied to the motor at a relatively higher voltage, for example, thirty-two volts. When this circuit has been maintained long enough for the starting motor 10 to perform its function, the hand lever 23 is released and the movable contact 22 is immediately returned to the position 30 by the action of the spring 35. This second energizing circuit for the motor may be traced as follows: From battery terminal 40 through conductor 41 to the motor 10, and then through conductors 42 and 49 to the stationary load contact 47, then through movable contact 48 and the frame or body of the magnetic switch 13, and then back to the terminal 50 of the battery through conductor 51.

The magnetic switch or contactor may be of any suitable construction, and, as shown in the drawing, may have a frame 52 which carries the magnet 53 and the movable armature 54. The frame 52 may be provided with a pivot or hinge pin 55 upon which the armature 54 is mounted to swing toward and away from the magnet 53. The

load contact 48 may be carried by the armature 54 and mounted thereon by means of a projecting flexible metallic arm or spring 56. The armature 54 may be acted upon by a weight 57 or the equivalent thereof to cause the same to swing on the pivot 55 in a direction to normally hold the contacts 47 and 48 open when the magnet 53 is deenergized.

The coil of the magnet 53 of the contactor 13 has a lead 58 at one end thereof which is connected to the switch body or frame and the other end of this magnet coil is connected to the stationary contact 21 of the switch 12 by means of the conductor 59. By reason of these connections for the magnet coil 53, it will be seen that when the switch contact 22 is moved into engagement with the stationary contacts 20 and 21 the magnet 53 is energized to cause closing of the load contacts 47 and 48. The energizing circuit for the magnet 53 may be traced from the battery terminal 40 through conductor 41, conductor 59 to stationary switch contact 20, then through movable switch contact 22 and stationary contact 21, and through conductor 59 to the magnet coil 53 and thence through conductor 58, the body of the switch 13, and back to battery terminal 50 through conductor 51. It will be noted from the circuits above traced that when the magnet 53 is energized by movement of the switch member 22 to its position 32, the high voltage energizing circuit for the starter motor 10 is then established through the load contacts 47 and 48 of the contactor and not through any of the contacts of the switch 12.

When the hand lever 23 is released, the movable contact 22 is returned to the position 30, as explained above, and the energizing circuit for the magnet 53 is broken. Normally, the deenergization of the magnet 53 allows the contact 48 to be moved away from the contact 47 by the action of the weight 57 and of the spring arm 56. However, in spite of the use of special alloys for the contacts 47 and 48, it is found that they frequently stick together and the energizing circuit for the motor 10 is not broken when it should be. To overcome this difficulty, I have provided the electromagnetic device 14 for causing positive opening of the load contacts 47 and 48. The device 14 may be of any suitable construction and may comprise a magnet coil or solenoid 60 with a movable core 61 arranged therein to cause a striker 62 to be projected through a guide member 63 whenever the solenoid or magnet coil is energized. The core and striker may be retracted upon de-energization of the coil 60, as by means of a suitably arranged spring 64. When the striker 62 is suddenly projected by energization of the coil 60, it strikes the extension 65 of the spring arm 56 and thereby causes the movable contact 48 to be moved away from the contact 47 to open the motor circuit.

The energizing circuit for the magnet of the device 14 is so arranged that it will be closed when the contact 22 of the switch 12 is returned to its position 30, provided the load contacts 47 and 48 remain closed. If the load contacts 47 and 48 are opened upon deenergization of the magnet 53, as they normally should be, the magnet 60 will not be energized when the contact 22 returns to its position 30. However, if the contacts 47 and 48 stick, the magnet 60 will be energized to cause outward movement of the striker 62 as soon as the contacts 17 and 18 are bridged by the contact 22. The energizing circuit for the magnet 60 may be traced as follows: From battery terminal 40 through conductors 41 and 66 to the magnet coil 75

and then through conductor 67 and contact strip 68 to the stationary contact 11 of the switch 12, then through movable contact 22, stationary contact 18, load conductors 43 and 48, load contacts 47 and 48, and through arm 56 and the body of switch 13, and then back to battery terminal 50 through conductor 51.

In Fig. 2 of the drawing I have shown my invention embodied in another control system which is of somewhat simpler form. This control system also includes a motor 10, which may be a motor for starting an internal combustion engine, and a storage battery 11 for supplying energizing current to the motor. A pair of load contacts 72 and 73 control the motor circuit and when closed cause the motor to be driven by current supplied from the battery. The opening of these contacts opens the motor circuit.

The load contacts 72 and 73 are closed by energization of the magnet 74 of the contactor or electromagnet switch 75. Contact 73 is carried on a spring arm 76 which is in turn carried by the armature 11 of the electromagnetic switch. The armature 11 may be hinged to the frame 78 of the electromagnetic switch by means of the hinge or pivot pin 79. The spring arm 76 has a part 80 projecting beyond the contact 73, and this projecting part is adapted to be engaged by a striker 81 in the event the contacts 72 and 73 remain closed after deenergization of the magnet 74. The striker 81 may be carried by a movable core 82 disposed within a magnet coil or solenoid 83 which is arranged to be energized whenever the contacts 72 and 73 remain closed as the result of sticking.

A manually operable starting switch 84 controls the energization of the magnets 74 and 83. This switch may have a pair of stationary contacts 85 and 86 representing first and second positions for a manually movable switch contact or arm 87. The contact 87 is normally held in, or returned to, its first or initial position in engagement with the contact 85 by means of a tension spring 88.

When the internal combustion engine is to be cranked, the switch member 87 is moved into engagement with the contact 86 and, by reason of the control circuit thereby established, the magnet 74 is energized and causes closing of the load contacts 72 and 73. The closing of these contacts causes the motor 10 to be operated by current supplied from the battery 11. When the switch member 87 is released, it is returned to its initial position in engagement with the contact 85 and the deenergization of the magnet 74 by the opening of the circuit thereof at the contact 86 permits the contacts 72 and 73 to be opened by the swinging of the armature 11. However, if the contacts 72 and 73 remain closed, for example as the result of sticking, the magnet 83 is energized to cause the striker 81 to suddenly engage the arm part 80 and open the load contacts. The energizing circuit for the magnet 83 is established through the contacts 85 and 87 of the switch 84 and through the contacts 72 and 73 when the latter remain closed.

It will be noted that in both of the control systems disclosed in the drawing the magnetically operated striker engages a part of the armature of the magnetic switch at a point relatively remote from the armature pivot or hinge. With this arrangement, the lever arm is such that only a light suddenly acting force need be applied to the armature to cause opening of the contacts in overcoming sticking thereof. I find that opening of the load contacts can be accomplished by

use of a relatively small magnet for actuating the striker and that the use of such a magnetically operated striker permits the magnetic switch for operating the load contacts to be of much simpler and lighter construction than would otherwise be the case. It will be observed, furthermore, that the operation of the striker is dependent upon a circuit established through contacts of the starter switch and also through the sticking load contacts, and that this arrangement provides for the energization of the striker magnet automatically and only in the event that the load contacts stick.

While I have described my improved control apparatus in a somewhat detailed manner, it will be understood, of course, that I do not wish to be limited to the precise arrangements described and illustrated in the drawing, but regard my invention as including such changes and modifications as do not involve a departure from the spirit of the invention and the scope of the appended claims.

Having thus described my invention, I claim:

1. In combination, a circuit, a pair of contacts in said circuit, a magnet adapted to close said contacts when energized and to permit opening of said contacts when deenergized, a circuit for said magnet, a switch having contacts controlling the magnet circuit, and magnetically operable means for opening said contacts in the event of sticking including a circuit established through contacts of said switch and through the sticking contacts.

2. In electric starting apparatus, the combination of a motor, a load circuit therefor, a pair of load contacts in said circuit, a magnet adapted to cause closing of said load contacts when energized and to permit opening thereof when deenergized, a circuit for said magnet, a switch having contacts controlling said magnet circuit, a member movable to cause opening of said load contacts, a magnet for actuating said member, and a circuit for the last mentioned magnet adapted to be established through contacts of said switch and through said load contacts.

3. In electric control apparatus, the combination of a load circuit, a pair of contacts in said circuit, a magnet adapted to cause closing of said contacts, a second magnet adapted to cause opening of said contacts, circuit connections for said magnets, and a switch having one position for energizing the first mentioned magnet and another position for energizing the second magnet, the circuit for the second magnet having the load circuit contacts therein whereby the second magnet is energized only if the load contacts stick.

4. In electric starting apparatus, the combination of a motor, a motor circuit, load contacts in the motor circuit, a magnet for closing said load contacts, a member movable to cause opening of the load contacts in the event of sticking thereof, a magnet for actuating said member, a switch having a member normally held in one position but movable to a second position, circuit connections for energizing the first mentioned magnet when the switch member is in said second position, and circuit connections for energizing the second mentioned magnet when the switch member is in said one position and said load contacts are closed.

5. In electric starting apparatus, the combination of a motor, a motor circuit, load contacts in the motor circuit, a magnet having a movable armature carrying one of said load contacts and adapted to cause closing of said contacts when energized, a striker adapted to engage said armature.

ture to cause opening of said contacts, a magnet adapted to actuate said striker when energized, a starting switch having a member movable to a starting position and automatically retracted when released, circuit connections for energizing the first mentioned magnet when said switch member is in said starting position, and circuit connections for energizing the second magnet to cause actuation of said striker whenever said switch member is moved to its retracted position and said load contacts remain closed.

6. In electric starting apparatus, the combination of a motor, a battery having terminals affording different voltages, a starting switch having a member normally held in an initial posi-

tion but movable to second and third positions, connections providing a low voltage load circuit for the motor when the switch member is in said second position, connections providing a high voltage load circuit for the motor, a pair of contacts in the high voltage load circuit, a magnet adapted to close said contacts when energized, connections for energizing said magnet when said switch member is in said third position, a magnet adapted to open said contacts when energized, and connections for energizing the last mentioned magnet when the switch member is in said initial position and said contacts of the high voltage load circuit are closed.

BENNETT M. LEECE. 15
